UNITED STATES PATENT OFFICE.

PERRY E. MYERS, OF MONROE CITY, INDIANA.

HINGE.

1,313,411.

Specification of Letters Patent.

Patented Aug. 19, 1919.

Application filed December 30, 1916. Serial No. 139,740.

To all whom it may concern:

Be it known that I, PERRY E. MYERS, a citizen of the United States, residing at Monroe City, in the county of Knox and

5 State of Indiana, have invented certain new and useful Improvements in Hinges; and I do hereby declare the following to be a full, clear, and exact description of the invention, such as will enable others skilled in the 10 art to which it appertains to make and use the same.

My invention relates to an improved hinge and is more particularly adapted for use in connection with gates and barn 15 doors.

One of the objects of my invention is to produce a hinge provided with means whereby the gate or door will be elevated when operated to open position so as to 20 prevent the gate or door from dragging the ground or other surface therebeneath, and which means will retain the gate or door in open position when desired, and also retain the gate or door in accurate alinement with 25 the gate or door posts when in closed position.

Another object of my invention is to produce a hinge provided with means for efficiently securing the hinge upon the gate 30 and the gate post whereby to obviate the possibility of the loosening of the hinge and the consequent sagging of the gate or door, as the case may be.

A further object of my invention is to 35 produce a hinge constructed in a manner to prevent the gate or door from being removed from its hinged position by stock or unauthorized persons.

A further object of my invention is to 40 produce a hinge which may be readily attached to an already completed gate or door, or which may be built in the gate or door during its construction.

A still further object of my invention is to 45 produce a hinge consisting of few parts, strong and durable, and which may be manufactured and sold upon the market at a nominal cost.

These and other objects and advantages 50 of my invention will more fully appear as the nature of the invention is more clearly understood from the following specification, the subject-matter of the claim, and the views illustrated in the accompanying 55 drawings, in which,

Figure 1 is a fragmentary side view of a gate and a gate post, showing one of the hinges in applied operative position thereon.

Fig. 2 is a sectional view on line 2—2 of 60 Fig. 1.

I desire to here state that for the sake of clearness and illustration, I have shown sufficient parts of a gate and the hinge post therefor to disclose the application of my 65 invention to a gate, but that my invention is not restricted to this exact application as the same is equally applicable to barn doors or other doors, and that while I have shown the preferred embodiment of my invention 70 I may make such expedient alterations and variations in the construction to meet the exigencies of the case, which will neither depart from the spirit of the invention nor the scope of the claim.

Referring to the drawings, wherein similar reference characters denote corresponding parts throughout the several views, 1 denotes the horizontal slats of the usual 75 form of gate, 2 the oppositely disposed vertical end slats, 3 the bolts, rivets, or other suitable means for securing together the respective slats of the gate, and 4 the adjacent hinge post for supporting the gate.

The hinge comprises two members one secured upon the gate and the other secured upon the gate post. The member upon the gate consists of the base plate 5, provided with the laterally projecting upper and lower arms 6, preferably rectangular in 80 cross section, and each being provided at its outer extremity with the shoulder 7 and the centrally disposed threaded stem 8, adapted to receive the elongated apertured cleat 9 and retained thereon by the nuts 10 85 threaded upon the stem 8. At the opposite side of the base plate 5 is provided the upper apertured ear 11 and the lower apertured ear 12. The upper and lower faces of the apertured ear 12 are formed straight, 90 and the upper face of the apertured ear 11 is also formed straight, but the lower face of the apertured ear 11 is formed with diametrically opposite concaved recesses 13, so formed in the under face of the apertured 95 ear 11 that the recesses 13 are disposed transversely of the longitudinal direction of the gate.

To secure the above described hinge member upon a gate the nuts 10 and the cleats 9 100

are removed from the threaded stems 8 of the arms 6. The arms 6 are then passed between the vertical slats 2 of the gate at any desired points, the arms 6 being preferably 5 of a width to fit snugly between the vertical slats 2, and until the base plate 5 engages the outer edges of the slats 2. The cleats 9 are then positioned upon the threaded stems 8 and the nuts 10 screwed upon the stems 8 10 against the cleats 9, whereby the edges of the vertical slats 2 of the gate will be bound between the base plate 5 and the respective cleats 9, thus efficiently securing this member of the hinge upon the gate, it being understood, of course, that two or more of these hinges may be employed as desired.

The member upon the post 4 consists of the base plate 14, provided in each of its four corners with an aperture, through 20 which apertures are designed to pass the screw bolts 15, which are screwed into the post 4 for securing the base plate 11 thereon. Formed upon the base plate 14 of this member of the hinge is the elongated tubular cylinder 16, whose longitudinal central bore is equal in diameter and registers with the apertures through the ears 11 and 12 of the base plate 5 of the gate member of the hinge. The lower face of the cylinder 16 is straight, 30 while the upper surface of the cylinder 16 is provided with the diametrically opposite convexed projections 17, which are also disposed transversely of the longitudinal direction of the gate and which projections 17 are seated within the recesses 13 of the ear 11 when the gate is in closed position, so that the gate will be maintained in accurate alignment with the gate post 4 and the jamb or latch post (not shown) at the opposite 40 end of the gate, but when the gate is swung to open position the respective portions of the under face of the ear 11 at each side of the recesses 13 will ride upwardly upon the respective projections 17 upon the upper face 45 of the cylinder 16 and thereby cause the gate to become elevated throughout its entire length to avoid contact with the surface of the ground therebeneath, the length of the cylinder 16 being sufficiently less than 50 the distance between the opposing faces of the ears 11 and 12 to provide for this vertical movement of the gate, and if desired, the gate may be held in open position by swinging the gate a sufficient distance outwardly 55 until the portions at each side of the recesses 13 of the ear 11 are moved beyond the projections 17 upon the cylinder 16 and begin to descend upon the sloping portions of the projections 17 which are opposite to the 60 sloping sides of the projections 17 which retain the gate in normal closed position, whereby the gate will be held open until the gate is moved inwardly sufficiently for the portions at each side of the recesses 13 of the 65 ear 11 to be returned to elevated position

upon the projections 17 of the cylinder 16, or if desired, the gate may be moved farther inwardly and thereby be automatically returned to normal closed position by the travel of the portions of the ear 11 at each 70 side of the recesses 13 downwardly upon the opposite inclined portions of the projections 17.

The cylinder 16 of the gate post member of the hinge is retained in its interposed position between the ears 11 and 12 of the gate member of the hinge by the headed bolt 18, which projects through the registering apertures of the ears 11 and 12 and the central bore of the cylinder 16, and is preferably 80 provided with a threaded lower end for receiving the nut 19 thereon for retaining the respective members of the hinge in operative relation with each other. However, the bolt 18 may be substituted by a headed pin if 85 desired.

In the event of the screw bolts 15 losing their treaded engagement with the gate post 4, or otherwise becoming loosened, and thereby causing the hinge to become loose 90 upon the gate post 4 and the consequent sagging of the gate, I provide against such contingencies by employing the reinforcing hoop 20, adapted to be passed through the opening or bore 21 formed transversely through the gate post member of the hinge, preferably at the point of juncture of the base plate 14 and the cylinder 16, and around the gate post 4, and in order to adjust the hoop 20 to accommodate the same to posts of 95 different diameters, I provide one end of the rod or bar comprising the hoop 20 with the laterally projecting apertured ear 22, and the other end of the rod or bar with the screw threaded portion 23, which is projected 100 through the apertured ear 22 and is provided upon the projecting portion of the threaded end 23 with the adjusting nut 24, which when screwed home upon the threaded end 23 against the ear 22 will reduce the 105 diameter of the hoop 20 to such a degree that the hoop 20 will bind around the gate post 4 and thereby aid the screw bolts 15 in 110 securely retaining the gate post member of the hinge upon the gate post 4.

To provide for sufficient outward swing of the gate in order that the gate may be retained in open position by the coaction of the member 13 of the ear 11 and the members 17 of the cylinder 16, which outward 115 swing of the gate may be interfered with by the edges of the base plate 5 contacting with the hoop 20 when the latter is employed, I preferably form in the side edges of the base plate 5 the notches 25, so that such a contingency will be guarded against and the gate free to swing outwardly in either direction as far as necessary to accomplish this result.

Having described my invention, what I 130

claim as new and desire to secure by Letters Patent, is:—

A gate hinge embodying a hinge member having a base plate to fit against a post, and having a cylinder and an opening between said plate and cylinder, a hoop to embrace the post extending through said opening between said base and cylinder, one end of the hoop having an outstanding ear and the 10 other end of the hoop extending through said ear, means on the last named end of the hoop bearing against the ear to contract the hoop on the post, a second hinge member

having a cylinder bearing on the aforesaid cylinder, and a hinge bolt extending through 15 said cylinders, the adjacent ends of the cylinders having depressions and projections for turning them to a predetermined position relatively.

In testimony whereof I have signed my 20 name to this specification in the presence of two subscribing witnesses.

PERRY E. MYERS.
